BUILDING CONSTRUCTION

Sverre F. Nielsen, San Diego, and Fred Bostad,
Los Angeles, Calif.

Application March 26, 1937, Serial No. 133,212

10 Claims. (Cl. 72—16)

Our invention relates generally to improvements in building structures and more specifically to walls, floor and roof construction and the method of assembling, erecting and connecting the same into a rigid and permanent building; and its objects are to dispense with the use of removable temporary forms into which concrete or other cementitious material is required to be poured; to provide prefabricated units for building with a system of assemblage created by the construction upon the ground of cementitious tie beams and columns capable of supporting and sustaining the completed structure; to assure a more speedy construction of building and less employment of labor than has heretofore been possible; to effect a greater saving in the cost of materials and building construction; to simplify the erection of buildings and to render more effective and serviceable the several units of construction after they have been permanently assembled. Other objects of our invention will appear as incorporated in other features more fully illustrated in the drawings and more particularly hereinafter described and set forth in the claims.

We are aware, in the present system of construction commonly employed by builders, that three methods are used; first, the erection of blocks or units, one on top of the other, with mortar and binding material between each unit; second, the erection of a frame of steel, concrete or wood, to which are attached in well known ways various kinds of insulating and finish materials; and third, the erection of a set of forms into which reinforcing steel or mesh is introduced, and concrete or other cementitious material is poured or applied.

Our invention introduces an entirely new system as we erect the prefabricated finish and insulating wall in units first, and by arrangement of ribs in these units apply the connecting and stiffening frame, consisting of columns or studs and beams afterwards, by use of cement gun concrete or similar method or material and application from one side without use of temporary forms for this application.

This procedure effectuates a considerable saving in labor and time at point of erection, as the units may be fabricated in a plant, and then later erected and tied together in one operation of construction, making possible a saving of more than half the construction time necessary under present methods. A rigid, fireproof, earthquake resistive and vermin-proof structure is also ob-

tained without the slow process of masonry construction or concrete pouring on the job.

The prefabricated units forming the wall may consist of reinforced concrete or other suitable materials, constructed with ribs to form spaces inclosed on two or more sides into which connections in form of columns or studs and tie-beams may be applied without use of temporary forms. By arrangement of ribs or clips in the wall units, floor and ceiling joists may be supported on the units before the columns and beams are applied, and thereby effectuate a rigid connection for transmittal of lateral forces through the beams, columns, and joists.

Prefabricated roof and floor units may be used with joints so formed as to permit filling with cement mortar or other cementitious materials. Wires, clips or bolts may be arranged so as to permit connection of units to joists, as well as tying sections together into one solid unit.

Attention is hereby directed to the drawings, in which similar numerals of designation refer to similar parts throughout the several views, and in which,—

Figure I is a perspective view partly in section, of a wall and corner of our improved building construction, showing a number of the beams and columns already erected, and one of the erection frames in sustaining position before the installation of the beams and columns adjacent thereto;

Figure II is a typical vertical section of a one story wall and adjacent floor and roof of our improved construction;

Figure III is a typical vertical section through a window of such construction, and

Figure IV is a typical horizontal section of our improved construction, showing a corner and jamb for a window or door opening.

Referring to the drawings, we preferably construct each prefabricated wall unit 1, with an elongated panel, and with vertical ribs 6 and horizontal ribs 1a and 1b, which ribs are for the purpose of strengthening such unit in handling and in erection and for providing necessary backing for the reception of columns 18 and tie-beams 17a and 17b, which are made of concrete or other cementitious material. Preferably the vertical abutting edges of the units 1 are so shaped as to form, adjacent to said edges and between the ribs 6, a wedged shaped channel 21 for the reception of one of the columns 18. Preferably each of said wall units is, as shown, of full story height.

The horizontal ribs 1a and 1b, each located a

short distance, respectively, from the upper and lower ends of the vertical ribs 6, are preferably each provided with a bevel surface 23. For the purpose of reinforcement of the beams 17a and 17b we construct each of said ends of the vertical ribs 6 with horizontal bores or holes through which extend the metal bars or wires 22. As shown, the said ends do not extend completely across the beams 17a and 17b, but are embedded therein, so that each beam is continuous in structure.

In the case of windows or doors, unit lintels 4 are supplied in such sizes as may be required, and where windows are contemplated the proper desired opening is secured by units 5 designed to accompany the same and to conform thereto, the structure of both lintels 4 and units 5 being generally the same as units 1. To support the said lintels and properly finish the openings so provided for doors or windows, jambs 3 may be supplied.

The roof or floor joists 16 may be of steel, concrete or other suitable material, and are supported upon the vertical ribs 6 until the tie beams 17 and the columns 18 are applied and hardened. These beams and columns may be cement gun concrete or other suitable cementitious materials applied under pressure and without the use of temporary molds or forms. Roof or upper floor units 19 are preferably installed with joints directly above one of the joists 16, only one of such joists being shown in Figure I, the remainder being shown removed for the sake of clearness. Wires or clips may be supplied to permit attachment to the joists as well as to the individual units, and the joints may be filled with mortar or similar material, making a slab rigid enough for the transmittal of horizontal forces. Furring for the support of interior finish may be attached to the ribs 6 by nails driven through said furring into nailing blocks 20 cast into said ribs at the time of manufacture.

In order to provide a means to facilitate the handling of units 1 and to permit the attachment of temporary erection hooks, we core each rib at desirable places and intervals with holes 8. Such holes also permit the insertion of dowels and reinforcing steel for the strengthening of connections and frame, and they may in suitable instances permit passage of conduits and piping. By the employment of a whaler angle 10, erection hooks 9, inserted through holes or slots in said angle, are temporarily secured to said holes 8 and serve to hold a number of the units 1 in place while the columns 18 and beams 17a and 17b are being installed and until they have become hardened. The whaler angle 10 is so positioned as to present to the face of each of the ribs 6 a straight edge. It is so arranged as to permit application of columns and beams in one operation without removing said angle, and is made adjustable by means of a clamp 11 attached to a threaded bolt projecting through two sections of material in the erection or supporting frame 13, which bolt is secured in position by the nut 14 on the threaded end thereof.

The frame 13 may be of wood, metal or other suitable material, and is preferably constructed with an upright 12, braces 25 and 26, and floor strips 27 and 28 resting upon the floor slab 24 or adjacent thereto. The strip 15 forming part of the said frame 13 may be used, where more than one frame is employed, to provide a support for temporary scaffolding, and if desired the frame

may be secured to the floor 24 by any suitable means.

In erecting and connecting the prefabricated units 1 in a building construction after the floor or floor slab 24 has been installed, we first place in proper position and at suitable spacing the removable erection frames 13 in such number as may be required, and temporarily attach the same to the floor in any suitable manner. At the same time we attach a whaler angle 10 to each frame, and align the straight edges of said whaler angles so as to present a straight support for the units along each wall. Preferably starting at one corner and continuing around the building, the units 1 are then placed in verti-position edge to edge upon the end surface of the floor slab 24 and secured thereto by dowel pins 29, so as to bear uniformly against the straight edges aforesaid, and the erection hooks 9 are affixed to the units and the whaler angles 10 firmly secured thereto. Thereupon the roof joists 16 and the slabs 19 are installed in the positions indicated in the drawings, the bars 22 being inserted as shown. Concrete or other cementitious material is then applied by a cement gun in the well known manner to fill the channels 21 and channels adjacent to the bevel surfaces 22 to form the columns 18 and tie-beams 17a and 17b constituting the connecting and stiffening frame supporting the general structure. After such material has become hardened, the temporary frames 13 are removed, and the walls finished in any desired manner, such as the installation of damp proofing and insulating materials against the erected wall, the attaching of furring strips. As a result of such construction, an integral supporting frame of reinforced concrete or other cementitious material applied by a cement gun is provided, all parts of which frame are thoroughly bonded together and to the prefabricated wall units, with integral structural connections capable of transmitting and resisting all lateral and vertical forces to which the structure may be exposed. By the use of the word "integral" as used in this connection and in the appended claims, we desire to be understood as indicating the definite structural bond between frame and units obtained by a pressure or "gun" application of the frame, as opposed to the pouring or running in place of a concrete frame which upon hardening furnishes no structural connection between frame and units, and is only equivalent to an ordinary mortar joint so far as structural strength is concerned.

Our invention may be embodied in other specific forms without departing from the spirit or essential characteristics thereof. The present embodiment is therefore to be considered in all respects as illustrative and not restrictive, the scope of our invention being indicated by the appended claims rather than by the foregoing description, and all changes which come within the meaning and range of equivalency are therefore intended to be embraced therein.

What we claim and desire to secure by Letters Patent is:

1. A system of building construction consisting of full wall height or story height panels, having near their vertical edges vertical inwardly directed ribs constructed to form vertical V shaped grooves between two adjoining units, and having near the horizontal edges inwardly projected ribs which together with the roof or floor or second tier of panels form horizontal channels.

2. A system of building construction consisting of full wall height or story height panels,

having near their vertical edges vertical inwardly directed ribs constructed to form vertical V shaped grooves between two adjoining units, and having near the horizontal edges inwardly projected ribs which together with the roof or floor or second tier of panels form horizontal channels, and said vertical ribs extending past the intersecting horizontal ribs to a point between said horizontal rib and the horizontal edge of the unit, said extended part of the vertical rib having a hole cored through it horizontally, permitting the placing of continuous horizontal reinforcing bars in the horizontal channels formed between the horizontal ribs and the roof or floor or second tier of panels in such a manner that these bars engage all vertical ribs.

3. A system of building construction consisting of full wall height or story height panels, having near their vertical edges vertical inwardly directed ribs constructed to form vertical V shaped grooves between two adjoining units, and having near the horizontal edges inwardly projected ribs which together with the roof or floor or second tier of panels form horizontal channels, together with cementitious material filled into the above mentioned V shaped vertical grooves and horizontal channels, thereby forming a continuous structural frame that is integrally connected to all units and thus welding all units together into a continuous wall.

4. A system of building construction consisting of full wall height or story height panels, having near their vertical edges vertical inwardly directed ribs constructed to form vertical V shaped grooves between two adjoining units, and having near the horizontal edges inwardly projected ribs which together with the roof or floor or second tier of panels form horizontal channels, and said vertical ribs extending past the intersecting horizontal ribs to a point between said horizontal ribs and the horizontal edges of the panels, thereby providing a support for roof or floor joists at the top of the units and in the horizontal channels formed between the upper horizontal rib and the underside of the roof slab, so that the ends of said roof or floor joists are projecting into and are anchored in the structural frame that is applied in the horizontal channels after erection of the joists.

5. A system of building construction, consisting of full wall height or story height panels or units, near the vertical and horizontal edges of which are located inwardly projected ribs, the outside face of which is on an angle with the edge of the panel; presenting after erection of several units and roof joists and slabs, a wall surface with the ribs forming together with the roof and floor, continuous horizontal channels at top and bottom, and vertical channels between the individual units terminating in the horizontal channels; all of said channels widening towards the inside face of the ribs, permitting projection of cement gun concrete or similar other material and application into said channels, horizontally and perpendicular to the sides resulting in a frame consisting of top and bottom tie beams and vertical columns or studs, integrally connecting and connected to the individual units.

6. A system of building construction, consisting of full wall height or story height panels or units, near the vertical and horizontal edges of which are located inwardly projected ribs which after erection of several units and floor and roof slabs, form continuous horizontal channels at the

top and the bottom of the wall, and vertical channels or V grooves between the adjoining units; together with narrower posts, the one side of which are shaped to receive window or door frame and the other side shaped similar to the ordinary units, said posts terminating at the top of the door or window openings, supporting a unit shaped similar to the ordinary units but of dimensions to fill in the opening above the door or window, said unit having the same ribs as the ordinary units except for the bottom rib which is shaped to receive the window or door frame, and reinforced to support the roof load from above; and together with units shaped similar to the ordinary units but of dimensions to fill in the opening between the posts and below the window, and the top rib shaped to receive the window, all the said units and ribs being so shaped as to provide horizontal channels at roof and floor line or at the joint with a second tier of units, and providing vertical V grooves or channels at the edges of each unit; thereby making possible the complete erection of the building against a temporary frame in one operation, and application of cementitious material horizontally projected into the channels and perpendicular to the sides of said channel in one continuous operation after the complete structure is erected, and providing a structural frame consisting of top and bottom horizontal tie beams and vertical columns or studs, integrally connecting and connected to the individual units.

7. In a system of building construction special posts extending from the floor or foundation to the underside of special panels over door, window or other openings, one side of the said post shaped to receive window sash or door frame, the opposite side to be sloping towards the inside in such manner that the post together with the adjoining panel shall form a vertical V shaped groove the open side of which faces the inside of the building in such manner that cement gun concrete or other pressure applied material can be projected into said groove horizontally and perpendicular to the sides of the groove and thereby resulting in an integral connection between the post and the adjoining panel.

8. In a system of building construction special bulkhead panels or wall panels extending from underside of window to floor, presenting along the top edge an inwardly directed rib the upper side of which is shaped to receive window sash and form finished window sill, and presenting near the bottom edge an inwardly directed rib located some distance from the edge of the panel to present between said rib, the projecting part of the panel and the abutting floor a horizontal channel, and presenting along the vertical edges an inwardly directed rib the one side of which continues on an angle directly to the vertical edge of the panel, thus forming together with the adjoining panel a vertical V shaped groove, this V shaped groove and before mentioned horizontal channel with the open side facing the inside of the building in such manner that cement gun concrete or other pressure applied material can be projected into said channels and grooves horizontally and perpendicular to the sides of the grooves and channels thereby resulting in an integral connection between the adjoining panels and panel and floor.

9. A system of building construction consisting of wall panels extending full wall height or between wall opening and floor or roof, these panels presenting along both vertical edges an

inwardly directed rib, the one side of which continues on an angle directly to the edge of the panel thus forming with the adjoining panels vertical V shaped grooves, and also presenting along the horizontal edges an inwardly directed rib, which when adjacent to floor or roof is located some distance from the edge of the panel thereby forming together with the projecting part of the panel and the abutting floor or roof a horizontal channel, when said horizontal rib is adjacent to wall opening the rib is shaped to receive sash or door frame, the open side of above mentioned channels and V shaped grooves to face inward towards the inside of the building in such manner that cement gun concrete or other pressure applied material can be projected horizontally into the channels and grooves, and perpendicular to the sides of said channels and grooves thereby resulting in an integral connection between the several panels, and in the forming of a continuous structural frame consisting

of vertical studs evenly spaced and terminating in, and integrally connected with, a continuous bond beam at floor and roof.

10. A system of building construction consisting of wall panels so constructed that these can be erected against a temporary frame work so that they form the complete finished exterior of a building and serve as supports for roof joists, and present on the inside face along all vertical joints and at roof and floor continuous grooves and channels in such manner that these channels when filled with cement gun concrete or other pressure applied material at the same time provide a continuous structural frame for the building and an integral connection between all the several parts of which the wall is constructed, thus resulting in a construction where no joint is weaker than the panel proper.

SVERRE F. NIELSEN. 20
